PORTABLE RADIANT HEATER

Joseph Howard Leeds, New York, N. Y.

Application November 14, 1950, Serial No. 12,979

Term of patent 7 years

(Cl. D81—10)

To all whom it may concern:

Be it known that I, Joseph H. Leeds, a citizen of the United States of America, residing at the city, county, and State of New York, have invented a new, original, and ornamental Design for a Portable Radiant Heater, of which the following is a specification, reference being had to the accompanying drawing, forming part thereof.

The figure of the drawing illustrates, in perspective, a portable radiant heater embodying my new design, both sides of the heater being substantially identical.

I claim:

The ornamental design for a portable radiant heater, substantially as shown and described.

JOSEPH H. LEEDS.
